DESIGN FOR A WRAP-AROUND TURBAN

Lena Karlen, New York, N. Y.

Application June 4, 1942, Serial No. 107,106

Term of patent 3½ years

To all whom it may concern:

Be it known that I, Lena Karlen, a citizen of the United States of America, residing in New York city, county of New York, and State of New York, have invented a new, original, and ornamental Design for a Wrap-Around Turban, of which the following is a specification, reference being had to the accompanying drawing, forming part thereof, wherein,

Fig. 2 is a rear view thereof; and

I claim:

The ornamental design for a wrap-around turban, substantially as shown.

LENA KARLEN.
